LOCK CONSTRUCTION

Henry F. Keil, Scarsdale, N. Y., assignor to
 Francis Keil & Son, Inc., a corporation of New
 York

Application February 20, 1934, Serial No. 712,124

22 Claims. (Cl. 70—108)

This invention relates to key-controlled locks and more particularly to so-called padlocks.

One of the objects of this invention is to provide a thoroughly practical, reliable, and dependable 5 padlock construction adapted dependably to contain spare parts for replacement or repair. Another object is to provide a construction of this character in which dependable and reliable control over such spare parts is achieved. 10 Another object is to provide a construction of the above character which will retain an adequate supply of spare parts and permit access thereto only when unlocked. Another object is to provide a construction of the above character which 15 may be readily disassembled for purposes of repair when unlocked but which cannot be disassembled when locked. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

25 In the accompanying drawing in which are shown several of the various possible embodiments of my invention,

Figure 1 is a perspective view of a padlock with the locking member in open position;

30 Figure 2 is a perspective view of a closure member that has been omitted from Figure 1;

Figure 3 is a view showing certain parts of the pin tumbler type of construction;

Figure 4 shows certain parts used where the 35 wafer or sheet metal type of tumblers are employed;

Figure 5 is a perspective view of a padlock having another embodiment of my invention applied thereto;

40 Figure 6 is an exploded perspective view of the padlock shown in Figure 5 with the locking member in open position, and

Figure 7 is a front elevation on a smaller scale, certain parts being broken away and other 45 parts shown in section, of a padlock construction showing one form of key-controlled locking means that may be employed for coaction with the padlock shackle and related parts.

Similar reference characters refer to similar 50 parts throughout the several views of the drawing.

As conducive to a clearer understanding of certain features of this invention, it might here be noted that one of the most aggravating and 55 troublesome disadvantages met with in padlock

constructions heretofore known is that, when a part of the mechanism breaks or requires replacement, great difficulty and delay are experienced in either obtaining such spare parts or replacements or in specially making them up. For example, the key plug employed in padlocks may be of the type utilizing pin tumblers and springs for the latter or it may be of any other suitable type, such as the type employing so-called wafer tumblers with springs for the latter. These 10 tumblers and springs and related parts are very small and are difficult to duplicate. Also many padlocks now in common use may be easily disassembled while in locked position thus being entirely inadequate protection against undesired 15 entry or the like. Many of these padlocks when disassembled for purposes of repair even when unlocked are so severely damaged thereby that they are beyond repair. One of the dominant aims of this invention is to provide a dependable 20 padlock construction embodying adequate spare parts so as to avoid such difficulties and disadvantages as have just been mentioned.

Referring now to the drawing and more particularly to Figure 1, I have shown a padlock construction which may be of any suitable or desired type or construction; illustratively, it comprises a casing or body 10 having pivotally and slidably mounted therein a U-shaped locking member 11 whose one shank 12 is slidably and 30 pivotally mounted in a suitable channel or guide-way 13 extending vertically at one end of the casing 10 and whose left-hand shank 14 is adapted, when swung into position and the member 11 pressed downwardly, to enter a channel 35 or hole 15. The body 10 has rotatably mounted therein a key plug indicated at 16 for operation by way of a key insertable at the bottom end of the body 10. The key plug 16 may be constructed to coact with the body or casing 10 in any suitable 40 manner, as by pin tumblers 18 and 118 and springs 19 (Figure 3) or as by the wafer type of tumblers 20 and springs 21 (Figure 4), as will be understood by those skilled in the art, and any suitable means, heretofore known, may be employed for causing the key plug 16 to prevent or permit the withdrawal of the locking member 11 upwardly or its rotation about the one shank 12 thereof. For example, the vertical shanks 12 and 14 may have notches 12a and 14a, respectively, 45 with which may coact members within the body 10 under the control of the key plug 16 and its associated key (not shown).

In Figure 7 I have shown, by way of illustration, how these parts may be arranged and constructed 55

and, turning to Figure 7, the key plug 16 is provided with a plurality of plug tumblers 18 of the pin tumbler type, receivable in suitable recesses in the key plug 16 for communication with the key slot; of the suitable or desired number of tumblers employed, two are shown in Figure 7.

The casing or bow 10 is provided with suitable recesses in which are slidably received the casing tumblers corresponding in number to the key plug tumblers 18 and, where two of the latter are shown in Figure 7, I have shown two respectively coacting casing tumblers 118; the latter are spring-pressed toward the right, as viewed in Figure 7, by their springs 19.

Accordingly, rotation of the key plug 16 is permitted or prevented according as the proper key is inserted in the key slot or not. And as above noted, the key plug 16 controls suitable members, shown in Figure 7 at 51 and 52 for coaction with the notches 14a and 12a in the shanks of the shackle 11. Any suitable means, diagrammatically indicated at 53 in Figure 7, may be employed to bring about the desired coaction of the members 51, 52 with the key plug 16 and the shackle 11, various such means being well known in the art.

On the top wall 22 of the casing 10 and integrally formed therewith is a four-walled chamber 23 made up of the left end wall 24, the right end wall 25, and the spaced side walls 26 and 27, the latter projecting upwardly beyond the former. The bottom of the chamber 23 may be formed in the same plane with the plane of the top wall 22 of the casing 10, or it may extend downwardly into the casing or body 10, if desired.

The length of the chamber 23 in a direction from the left to the right is slightly less than the spacing between the shanks 12-14 of the locking member 11, and the width of the chamber 23, that is, the spacing of the side walls 26-27, may be commensurate with the thickness of the body 10.

The upwardly extended portions of the side walls 26-27 are undercut, as at 26a and 27a, respectively, to form guideways whose base portions are in the plane of the top faces of the end walls 24-25. Into these slideways is received a closure member 28 (Figure 2) having its side edges beveled as at 28a and 28b to be snugly and relatively tightly and slightly received in the undercut guideways 26a-27a, respectively, closure member 28 being of a length commensurate with the outside dimension or length of the end walls forming the chamber 23.

The walls forming the chamber 23 are preferably cast or otherwise integrally formed with the body 10.

In this chamber 23 I place duplicates of the springs, tumblers, and other small parts that go to make up the padlock construction. Typically or illustratively chamber 23 may contain tumblers and springs like those shown in Figures 3 or 4, depending upon the key plug construction that is employed.

Under certain circumstances, chamber 23 may be bottomless thus opening into the interior of casing 10. Of course, when so constructed, the casing cannot be used for storage of spare parts but is a convenient means of gaining access to the interior of the casing for purposes of disassembly or repair.

The closure 28 is forced into place, being frictionally held against being dislodged but being provided with a depression 28c in its top face to permit it to be moved with the fingernail or with a tool.

When the chamber 23 is closed by the member 28, thus to enclose the spare parts, access to the latter can be gained only with the aid of the key (not shown) which is necessary to release the locking member 11, thus to permit it to be moved or swung away from the end wall 24 and thus to permit the member 28 to be withdrawn to gain access to the spare parts.

Thus the construction carries with it repair parts and, moreover, does so in a manner as to prevent unauthorized tampering therewith.

Turning now to Figure 5, I have shown a padlock generally indicated at 29 which, like the padlock shown in Figure 1, may be of any suitable construction having a casing 30 and a U-shaped locking member generally indicated at 31. Member 31 is free to slide longitudinally with respect to casing 30, thus having a short end 33 and a long end 34. End 34 is permanently seated within the casing 30 and the member 31 may pivot thereabout as an axis after being moved into the open position shown in Figure 6.

As more clearly shown in Figure 6, I provide a channel 35 formed in the side of casing 30 adjacent end portion 33 of member 31. Channel 35 preferably extends throughout the entire length of the casing 30 and has inwardly beveled walls 35a and 35b. Extending into the face of channel 35 is a suitable compartment 36 wherein I prefer to store several repair parts generally indicated at 37 preferably similar in general character to the parts described above to be stored in chamber 23. An aperture 38 in the bottom of channel 35 forms one end of the recess wherein the bolts for locking member 31 in its closed position are located. A hole 39 in the bottom of channel 35 is thus formed therein and preferably retains a pin for holding in operative position certain of the interior parts of the lock, as, for example, the lock cylinder (not shown). Thus with a lock 40 of this construction when channel 35 is exposed as shown in Figure 6 and the lock is turned so that the bottom of channel 35 is uppermost, the pin in hole 39 falls out as do the locking bolts, thus to afford a quick disassembly of the entire 45 mechanism.

When the member 31 is in its locked position (Figure 5), end portion 33 extends through a suitable hole 40 in casing 30 as shown in Figure 6. A suitable recess 41 surrounds hole 40 to provide a shoulder 41a. Thus a cover 42 having beveled walls corresponding to walls 35a and 35b is provided which may slide into channel 35 having been placed in endwise relation thereto. Cover 42 has a right angle extension 43 which fits within recess 41 and has a hole 44 extending therethrough in registry with hole 40. A screw 45 extends through a hole 46 in cover plate 42 and is threaded into hole 39 to hold the cover plate in the closed position shown in Figure 5.

Suitably formed upon member 31 substantially adjacent end portion 33 are a pair of lip portions 47 and 48. Thus when member 31 is in its closed and locked position (Figure 5), lips 47 and 48 abut against right angle projection 43 of cover plate 42 thus to prevent any movement of the plate with respect to casing 30 even when screw 45 is removed.

It will now become clear that it is impossible to remove cover plate 42 from casing 30 when the member 31 is in locked position. However, when repair is desirable, the lock may be opened, thus swinging end portion 33 away from right angle projection 43 (Figure 6), and, upon the removal of screw 45, cover plate 42 may be re-

5 moved to expose the interior of the lock. As pointed out above, the spare parts 37 are then readily accessible and also the various parts of the lock may be disassembled by the simple process of turning the casing upside down. Of course it should be understood that this construction might be applied to a lock wherein disassembly might be achieved in some other manner after the removal of cover plate 42 without departing 10 from the scope of this invention.

10 Accordingly, I have provided a thoroughly practical and efficient construction in which the several objects hereinabove referred to are efficiently and successfully accomplished.

15 As many possible embodiments may be made of the above invention and as many changes might be made in the embodiment above set forth, it is to be understood that all matter hereinbefore set forth, or shown in the accompanying drawing, is 20 to be interpreted as illustrative and not in a limiting sense.

I claim:—

25 1. In a padlock, in combination, a casing having a key-controlled locking member movable relative to the casing, means forming a chamber for carrying spare parts and a closure for the latter, means movably mounting said closure member relative to said casing said closure member being positioned to be freed for movement 30 only when said key-controlled locking member is moved relative to said casing.

35 2. In a padlock, in combination, a casing, a U-shaped locking member movably carried by said casing, a chamber positioned on said casing within in the space between the shanks of said U-shaped locking member when the latter is in locked position, and a closure member for said chamber movable in a direction such that movement thereof can take place only when said U-shaped locking 40 member is released and has changed its position relative to the casing.

45 3. In a padlock, in combination, a casing, a U-shaped locking member movably carried by said casing, a chamber positioned on said casing within in the space between the shanks of said U-shaped locking member when the latter is in locked position, said chamber having slideways extending in the direction of the line joining the vertical shanks of said U-shaped locking member, and a 50 closure member for said chamber slidably mounted in said slideways whereby said vertical shanks preclude movement thereof when said U-shaped member is in locking position.

55 4. In a padlock construction, in combination, a casing having a U-shaped locking member and key-controlled means for controlling the position of said member relative to said casing, and means whereby said casing has a chamber for receiving spare parts, said chamber having a closure member, movement of said closure member controlled by said U-shaped locking member.

60 5. In a padlock construction, in combination, a casing, an interior chamber having beveled edges formed within said casing, a sliding cover plate for said chamber, the edges of said plate beveled to engage said beveled edges of said chamber and means for preventing the removal of said cover plate when the padlock is locked.

65 6. In a padlock construction, in combination, a casing having a recess, means forming a chamber within said casing, a plate adapted to cover said chamber, and a locking member external to said casing but actuated by means within said casing adapted to enter said recess, said recess being

adjacent said plate, and thereby to lock into a position adjacent said plate to prevent the removal of said plate.

7. In a padlock construction, in combination, a casing retaining the working parts of the lock and having an open portion exposing some of said parts, the edges of said open portion being beveled, a slideable cover plate the edges of said plate beveled to engage said beveled edges of said open portion fitting over said open portion, and means 10 for preventing the removal of said plate when the padlock is locked. 5

8. In a padlock construction, in combination, a casing retaining the working parts of the lock and having an open portion exposing some of said 15 parts, said casing having a recess adjacent said open portion, a cover plate fitting over said open portion, and a locking member comprising a shackle adapted to enter said recess adjacent said open portion and to thereby coact with and to 20 lock said cover plate in said position.

9. In a padlock construction, in combination, a casing, a U-shaped locking member extending therefrom, said casing having an opening adjacent one end of said U-shaped locking member, 25 and a cover member adapted to fit over said opening and having an end portion through which said last-mentioned end of said locking member extends, said locking member adapted to hold said cover member in position when locked. 30

10. In a padlock construction, in combination, a casing having an opening formed in one portion thereof, a chamber within said opening, a cover member adapted to fit over said opening, and a U-shaped locking member adapted to hold said 35 cover member in position when locked.

11. In a padlock construction, in combination, a casing having an opening in one side thereof, said opening having sides beveled inwardly, a cover member adapted to slidably fit within said 40 opening, and means for holding said cover member in position when said lock is locked.

12. In a padlock construction, in combination, a casing having an opening in one side thereof, said opening having sides beveled inwardly, a 45 chamber connected with said opening, a cover member adapted to slidably interfit with said opening to close said opening, said cover member having a portion extending over one end of said casing, and a locking member adapted to 50 extend through said portion of said cover member to lock said cover member in position over said opening.

13. In a padlock construction, a lock casing having a storage chamber therein whose walls 55 are integral with said casing, said chamber having an opening at a face of the casing, locking mechanism within said casing, means securing said locking mechanism within said casing, a sliding plate adapted to cover said opening of 60 said chamber, and means independent of said securing means to lock said cover plate in closed position, said last-mentioned means being operable to release said plate by the actuation of said locking mechanism within said casing. 65

14. In a padlock construction, in combination, a lock casing having therein and retaining the working parts of the lock, said casing having a storage chamber, and an open portion adjacent to said storage chamber exposing some of said 70 parts therein, means accessible and operable through said open portion for holding and retaining said working parts in assembled relation to said casing, a closure member adapted to close both said storage chamber and said open portion, 75

and means for locking said closure member in closed position.

15. In a padlock construction, in combination, a lock casing having a chamber and a recess therein, said chamber having an opening in a face of said casing, a closure member for said opening having an orifice therein, and a U-shaped locking member associated with said casing, one end of said U-shaped member engaging through 10 said orifice in said cover plate and entering said recess and retaining said cover plate in locked position over said chamber when said U-shaped locking member is in closed position.

16. In a padlock construction, in combination, 15 a lock casing, means forming a chamber within said casing and opening on a side thereof, a cover plate for said chamber, an angled portion having a hole therethrough, said angled portion of said cover adapted to abut against an end of said 20 casing, a U-shaped locking member associated with said casing, said casing having an opening therein registering with one end of said U-shaped locking member, means to free said end of said U-shaped locking member from said opening and 25 means whereby said opening in said casing and said opening in said angled portion may be simultaneously engaged by said end of said U-shaped member whereby to hold said cover in locked position.

30 17. A padlock construction as claimed in claim 16 in which the walls of the means forming the chamber on the said side of the lock casing are provided with grooves and in which the said cover plate is slidably fitted into said grooves to slide 35 in the direction of its own plane lengthwise of the said side of said casing and toward said one end of said U-shaped locking member, the said one end of said U-shaped locking member having means positioned in the path of sliding movement 40 of said cover plate and acting to block said sliding movement when said one end of said U-shaped member enters said opening in said casing.

18. A padlock construction as claimed in claim 16 in which the casing has means, underneath 45 said cover plate and accessible only when the latter is moved into chamber-uncovering position, for holding within the casing means for controlling said U-shaped locking member.

19. In a padlock construction, in combination, 50 a casing having formed therein a chamber which has an opening exposed to the exterior of said casing, a plate-like closure for said chamber, lock means carried by and within said casing,

means movably mounting said plate-like closure for movement in its own plane into chamber-closing or chamber-opening position, and means under the control of said lock means for controlling movement of said closure. 5

20. In a padlock construction, in combination, a casing having, in a side thereof, two adjacent chambers open at and thereby exposed through the said side of said casing, an end wall of said casing having a recess communicating with one of said chambers, lock means within said casing, a locking member controlled by said lock means and movably mounted relative to said casing for entry through said recess in said end wall, a cover member interfitting with said casing and 15 extending over said two adjacent chambers, and means whereby said locking member, when entered into said recess, blocks movement of said cover member.

21. In a padlock construction, in combination, 20 a casing having, in a side thereof, two adjacent chambers open at and thereby exposed through the said side of said casing, an end wall of said casing having a recess communicating with one of said chambers, lock means within said casing, a 25 locking member controlled by said lock means and movably mounted relative to said casing for entry through said recess in said end wall, an L-shaped cover member whose one portion extends over said two chambers and whose other portion extends in substantial alignment with said end wall, and means whereby said locking member coacts with said other portion of said cover member to hold it in chamber-closing position. 30

22. In a padlock construction, in combination, 35 a casing having, in a side thereof, two adjacent chambers open at and thereby exposed through the said side of said casing, an end wall of said casing having a recess communicating with one of said chambers, lock means within said casing, a 40 locking member controlled by said lock means and movably mounted relative to said casing for entry through said recess in said end wall, and L-shaped cover member whose one portion extends over said two chambers and whose other portion extends in substantial alignment with said end wall, said other end portion of said cover member having a recess in substantial alignment, 45 when said cover member is in chamber-closing position, substantially aligned with the recess in 50 said end wall, whereby said locking member also enters the recess in said cover member.

HENRY F. KEIL.
